UNITED STATES PATENT OFFICE.

AUSTIN R. DICKINSON, OF SYRACUSE, NEW YORK.

DESIGN FOR A CURRYCOMB.

SPECIFICATION forming part of Design No. 24,245, dated April 23, 1895.

Application filed February 15, 1895. Serial No. 538,588. Term of patent 14 years.

To all whom it may concern:

Be it known that I, AUSTIN R. DICKINSON, a citizen of the United States, residing at Syracuse, in the county of Onondaga and State of New York, have invented and produced a new and original Design for a Currycomb, of which the following is a full, clear, and exact description, reference being had to the accompanying drawing, which forms a part thereof.

5 The figure in the accompanying drawing represents a perspective view of my improved design.

The leading or characteristic features of my design consist of the rectangular back-plate, having short curved pieces or horns arranged 5 near the front ends of the plate, beginning at a point near the edge of the back-plate and

projecting forward and outward therefrom beyond the outlines of said back-plate.

The letter A indicates the back-plate; B, the 20 curved pieces or horns, and C the handle. One end of each of the pieces or horns projects outward from the side edges of the back-plate, and the inner ends, curving downward, extend toward the handle C.

25

The design presents to the eye an attractive and pleasing effect.

What I claim is—

The design for a curry comb, substantially as herein shown and described.

AUSTIN R. DICKINSON.
